DESIGN FOR A CHAIR OR THE LIKE

Edward F. Crowley, New York, N. Y.

Application February 3, 1939, Serial No. 82,757

Term of patent 3½ years

To all whom it may concern:

Be it known that I, Edward F. Crowley, a citizen of the United States and a resident of the city of New York, in the county of Queens and State of New York, have invented and produced a new, original, and ornamental Design for a Chair or the like, of which the following is a specification, reference being had to the accompanying drawing, forming part thereof, wherein:

Fig. 1 is a side elevational view of a chair or the like showing my new design;

Fig. 2 is a front elevational view of the same, and

Fig. 3 is a top plan view thereof.

I claim:

The ornamental design for a chair or the like, as shown.

EDWARD F. CROWLEY.
